BALANCE MECHANISM FOR WATCHES
AND CLOCKS

James English, Winsted, Conn.

Application May 26, 1949, Serial No. 95,509

4 Claims. (Cl. 58—117)

1

This invention relates to balance mechanism for watches and clocks and more particularly to a balance wheel and hair spring for use on such mechanisms.

An object of this invention is to provide a balance mechanism of a novel and simpler construction than those heretofore used.

A further object of this invention is to provide a novel hair spring for a balance mechanism which is highly efficient in its operation and less costly to produce than the conventional types of helical springs heretofore used for balance wheels of clock mechanisms.

A still further object of this invention is to provide such a hair spring which may be readily and accurately adjusted for varying the speed of the balance wheel in order to correct any errors in the operation of the timing mechanism.

Further objects and advantages will be more clearly understood from the following description and the accompanying drawings in which:

Fig. 1 is a plan view showing portions of a balance mechanism embodying my invention.

Fig. 2 is a side view thereof partly in section.

Fig. 3 is a plan view of a portion of the mechanism shown in Fig. 1 but in a different position.

Fig. 4 is an enlarged fragmental top view showing the balance wheel and related parts.

Fig. 5 is a side view thereof showing some of the parts in section.

Fig. 6 is a plan view illustrating the operation of the balance wheel when adjusted for a fast speed.

Fig. 7 is a similar view showing the operation of the balance wheel when adjusted for slow speed.

As illustrated in the drawings, the numeral 5 denotes a member forming a portion of the casing on which is mounted a frame 6 of a timing mechanism which includes a main spring, not shown, that drives an escapement wheel 7 through a series of gears and pinions such as illustrated.

An escapement rocker arm 8 is pivotally mounted in the said frame, by means of a staff 9, and is rocked by teeth on the escapement wheel 7 which engage escapement cam pins on said rocker arm in the conventional manner well known to those skilled in the art.

The said rocker arm has a portion 10 extending therefrom with a slot therein which receives a pin 11 projecting perpendicularly from the balance wheel 12 for oscillating the said balance wheel in the conventional manner. The said balance wheel is pivotally mounted on the frame

2

6 by means of a staff 13 which rotates in pivots in said frame including the usual adjustable pivot 14 that is preferably in the form of a screw.

In the embodiment of the present invention, the balance wheel is provided with an opening 15 which extends therethrough and has parallel sides 16 and 17 at opposite sides of a radial axis, as indicated at 18 in Figs. 6 and 7.

My invention also provides a novel hair spring, as illustrated at 19 in the drawings. This hair spring preferably consists of a straight length of spring wire, which may be flat or round, and is fastened, at 20, to an end of an adjusting lever 21 which is pivotally mounted on a supporting bracket 22 by means of a pivot pin 23 that is adapted to fractionally retain said lever in adjusted position on the bracket 22.

The hair spring 19 projects from the end of the lever 21 through the opening 15 in the balance wheel and may be adjusted for varying the speed of said balance wheel as will be herein-after described.

It will be noted, from Figs. 6 and 7, that the degree of oscillation of the balance wheel 12 will vary indirectly with the distance of the hair spring 19 from the axis of said wheel. Therefore, in the position shown in Fig. 6, the hair spring, being positioned near its far position relatively to the said axis, will engage the opposite parallel walls 16 and 17 and limit the oscillating movement of the balance wheel to the distance indicated at (a), which is a relatively short distance, and the oscillating speed of the balance wheel is thereby increased since it is permitted to make more strokes per minute.

As illustrated in Fig. 7, the hair spring 19 is located in its near position relatively to the axis of the balance wheel. This permits the wheel to oscillate for the distance indicated at (b) and thereby reduce the oscillating speed of the balance wheel so that it will make fewer strokes per minute.

It will be understood that the oscillation of the balance wheel for the distance indicated at (a) is enough to move the rocker lever 10 for a sufficient distance to permit the intermittent rotation of the escapement wheel 7 and that the said escapement wheel will move for the distance of one tooth for each oscillation of the balance wheel regardless of whether the balance wheel oscillates for the distance (a) or (b).

In the operation of my improved balance mechanism, the hair spring 19 may be adjusted for its position relatively to the axis of the balance wheel 12 by merely swinging the lever 21

on the pivot 23 in either direction. If it is desired to increase the speed of the timing mechanism, the hair spring is moved outwardly to the position illustrated in Fig. 6 and, if it is desired to reduce the speed of said mechanism, the hair spring is moved inwardly to the position illustrated in Figs. 5 and 7. The said lever 21 is preferably held in adjusted position by friction between it and the bracket 22, but, if desired, the pivot screw 23 may be tightened to lock the lever 21 in adjusted position.

It will be understood that the variation in the length of the oscillating stroke of the balance wheel is caused by reason of the fact that the sides 16 and 17 of the opening 15 are parallel and thereby reduce or increase the distance traveled by the said wheel in accordance with the position of the hair spring 19 relatively to the axis of the balance wheel. The hair spring 19 acts merely as a resilient stop for each oscillating movement of the balance wheel and controls the distance traveled by said wheel so as to increase or decrease its stroke and thereby increase or decrease the number of strokes per minute and accordingly vary the speed of operation of the timing device.

It will be noted that the rocker arm 8 is formed flat and of a single piece of material and has a slot which receives the pin 11. It will be further noted that the outer end of the slot is closed to prevent disengagement between the said arm and pin during the operation of the balance wheel. Such disengagement, if it were to occur, would not only render the clock inoperative but also render it possible to throw the clock out of beat. If the clock should be handled in a violent manner during transportation or use, and such handling causes the balance wheel to oscillate through an arc greater than that permitted by the hair spring when in its downwardly inclined position, the closed slot will prevent the pin 11 from becoming disengaged from the arm 8.

By constructing the rocker arm as above described, the necessity of notching the balance shaft to provide a clearance for the rocker arm is eliminated thereby permitting the said balance shaft to be manufactured more accurately and more inexpensively.

I claim:

1. In a timing mechanism comprising a frame having an upper and a lower plate, a train of gears including an escapement wheel mounted between said plates, means for driving said mechanism, a balance wheel operated by said escapement wheel for controlling the speed of said mechanism, and adjustable stop means for variably limiting the length of the oscillating stroke of said balance wheel to thereby increase or decrease the number of strokes per minute of said balance wheel; said stop means including a resilient spring member pivotally connected to said frame and projecting therefrom through an opening in said balance wheel having spaced walls at opposite sides thereof abutting said spring member.

2. In a timing mechanism comprising a frame, a gear train including an escapement wheel, means for driving said mechanism, and a balance wheel for controlling the speed of opera-

tion of said mechanism; said balance wheel being pivotally mounted between said frame and deriving oscillating movement from said escapement wheel, and stop means for limiting the length of the oscillating strokes of said wheel to thereby increase and decrease the number of said strokes in a given time; the said stop means including a resilient spring member pivotally connected to the top plate of said frame and extending therefrom through an opening in said balance wheel, and cooperating linear abutments at opposite sides of said opening engageable with said spring member in different adjusted positions for limiting the length of the oscillating stroke of said balance wheel in proportion to the distance between the said spring member and the axis of the balance wheel.

3. In a timing device, a balance mechanism including a pivotally mounted balance staff, a balance wheel supported on said staff, means imparting oscillating movement to said wheel and controlled thereby, and stop means for variably limiting the length of the oscillating strokes of the said wheel to thereby increase and reduce the number of strokes in a given period of time; the said stop means including an opening in said wheel having spaced parallel elongated sides disposed at opposite sides of an axis extending radially from the fulcrum of said wheel, a support, a hair spring member mounted on said support and extending therefrom on a plane with the axis of said staff and through said opening for abutment with said walls to limit the length of the oscillating strokes of said wheel, and means for adjusting the said hair spring member to different distances from the axis of said staff to locate said spring member for abutment with different portions of said walls and thereby varying the length of the oscillating strokes of said wheel in accordance with the distance of said spring member from the said axis.

4. In a timing mechanism comprising a gear train and a balance wheel for controlling the operation of said gear train, stop means for limiting the oscillating stroke of said wheel including a resilient member, and elongated spaced abutments on said wheel engageable with said member at different distances from the fulcrum thereof for varying the oscillating strokes of said wheel; the said abutments being so disposed relatively to each other that the length of the said strokes is increased as the point of contact between the resilient member and the abutments is moved nearer to the fulcrum of said balance wheel.

JAMES ENGLISH.
